HOEN PRESS

Don L. Cleveland, Mount Gilead, Ohio, assignor to
The Hydraulic Press Corp. Inc., Wilmington,
Del., a corporation of Delaware

Application September 28, 1937, Serial No. 166,228

6 Claims. (Cl. 153—49)

This invention relates to presses, and in particular, to horn presses having a projecting member upon which the workpiece is supported.

One object of this invention is to provide a horn press having means for supporting the projecting portion or horn so as to prevent the breakage thereof under excessive pressures.

Another object is to provide a horn press, wherein the horn is movable into and out of engagement with a support which suspends the free end of the horn, thereby preventing the bending or breakage of the horn under excessive pressures.

Another object is to provide a horn press of the type described above, wherein the horn is movable away from engagement with a horn support in order to insert and withdraw the workpiece, but is moved into engagement with the support while the workpiece is being worked upon, this support being arranged to suspend at least one end and preferably both ends of the horn during the working operations upon the workpiece.

Another object is to provide a horn press having a separable horn and horn support for supporting the free end of the horn during loading and unloading operations, together with a workpiece support, preferably adjustable and operatively connected to the press platen so as to lift the workpiece when the platen rises.

Another object is to provide a horn press with an adjustable work support, as described above, wherein means is provided for simultaneously adjusting the position of the opposite ends of the support.

In the drawings:

Figure 1 is a front elevation of a press comprising one embodiment of the invention.

Figure 2 is a side elevation, partly in section, along the irregular line 2—2 showing the embodiment of the horn press illustrated in Figure 1.

Figure 3 is a diagrammatic front elevation of a horn press according to this invention, showing the platen, the horn and the work-support in their raised positions for the insertion and withdrawal of the workpieces.

Figure 4 is a diagrammatic side elevation of Figure 3, with one side of the press broken away to disclose the interior more clearly.

Figure 5 is a view similar to Figure 3, but with the work-support and horn lowered into the working positions, the platen being in its raised position.

Figure 6 is a side elevation similar to Figure 4 of the horn press in the position of Figure 5.

Figure 7 is a front elevation, similar to Figures

3 and 5, but with the work-support, the horn and the platen in their lowered or working positions.

Figure 8 is a side elevation, similar to Figures 4 and 6, but showing the press elements in the positions of Figure 7.

Figure 9 is a diagrammatic view showing the mechanism for simultaneously adjusting the position of the work-support relatively to the platen.

Figure 10 is a front elevation of the mechanism shown in Figure 9.

Figure 11 is a view of a typical workpiece, such as an automobile wheel rim, before being worked upon in the horn press.

Figure 12 is a view of the workpiece of Figure 11 after it has been pressed in the horn press to more nearly the correct shape.

Figure 13 is a view of the workpiece of Figures 11 and 12 after it has been pressed to shape and welded.

In general, the horn press of this invention consists of a movable horn or forwardly projecting member which carries the lower die, upon which the workpiece rests. This movable horn is arranged in one position to rest upon a support, which supports it at least at its free end, and preferably at both of its ends. The horn is arranged to be picked up by rods attached to the main platen, and moved upwardly as the main platen moves upwardly, so as to move the free end of the horn away from the horn support and permit the workpieces to be inserted or withdrawn. Optionally, a workpiece support is provided for supporting the lower portions of the workpiece below the horn, and likewise operatively connected to the platen to be moved upwardly as the platen moves upwardly to the loading and unloading positions. When the platen moves downwardly the horn is lowered into engagement with its horn support, and the work-support likewise moves downwardly. An adjustment is provided for raising and lowering the work-support relatively to the horn so as to adapt the former to different sizes of workpiece.

Hitherto, horn presses have been provided for pressing operations upon workpieces whose continuous extent or form required a forwardly projecting member for the workpiece to rest upon. Such presses, called horn presses by reason of the horn-like projection of the workpiece rest, have been subject to the defect that when high pressures were exerted upon the horn the latter would bend and frequently be broken off. In the present invention, however, the horn and the horn support are movable relatively to each other into and out of engagement so that the horn is supported

at both of its ends, and is therefore not subject to bending or breakage.

Referring to the drawings in detail, Figures 1 and 2 show a typical embodiment of the horn press of this invention in a commercial installation. This press is provided with top and bottom members 10 and 11, interconnected by strain rods 12. On the top member 10 is supported a main cylinder 13, having a surge tank 14 thereabove for containing fluid. A pump 15, preferably of the reversible variable delivery type, is operated by an electric motor 16 for supplying fluid to the main cylinder 13 for operating the main plunger or ram 17, to which is attached the main platen 18. Mounted upon the lower surface of the main platen 18 is the die carrier 19, having the upper die 20 secured thereto.

Suspended from the platen 18, as by the rods 21, is the horn carrier 22 which is guided, as at 23, by the strain rods 12 as it moves up and down under the influence of the rods 21 and main platen 18. Secured to the horn carrier 22 is the vertical portion 24 of the horn assembly, generally designated 25, and having a horizontal portion 26 extending forwardly from the vertical portion 24. The horizontal portion 26 is provided with the lower die 27, resting thereon and adapted to support the portion of the workpiece which is acted upon by the upper die 20. The rods 21, which raise and lower the horn carrier 22 in response to the motion of the main platen 18, are provided with enlarged heads 28 immediately beyond the holes 29, through which the rods 21 pass.

The bottom member 11 of the press is provided with a base 30 from which rises the front and rear arms 31 and 32 of the horn rest, generally designated 33 (Figure 2). The arms 31 and 32 are spaced apart a sufficient distance to support the front and rear ends of the horizontal horn member 25 and leave a cavity or space 34 extending downwardly away from the horn a greater distance than the extent of the workpiece 35 and into which the workpiece 35 may extend downwardly while suspended from the lower die 27 on the horn portion 26. The horn support arms 31 and 32 may be provided with recesses 36, into which fit corresponding projections 37 (Figure 3), upon the lower sides of the horizontal horn member 26. The latter may also be provided with an additional downward projection 38, adapted to fit into the space separating the front and rear horn supports 31 and 32, respectively.

Secured to the main platen 18 and extending downwardly therefrom are the threaded rods 39, having threaded portions 40 engaged by nuts 41 (Figure 3) mounted upon an H-shaped cross member 42, the cross bar of which passes through the space 34 between the front and rear arms 31 and 32 of the horn support 33. The nuts 41 (Figures 9 and 10) are attached to sprockets 43 engaged by a sprocket chain 44, which is likewise engaged by a sprocket 45 mounted on a vertical shaft 46 carrying the bevel gear 47. The latter meshes with a bevel gear 48 on a shaft 49, carrying a hand wheel 50. By rotating the hand wheel 50 the sprockets 43 and nuts 41 are caused to rotate simultaneously, thereby raising and lowering the cross member means 42 upon the threaded portions 40 of the rods 39.

In Figures 3 to 8, inclusive, the form of press shown is substantially the same as that in Figures 1 and 2, but is simplified and the rods 39 are placed upon the outside of the strain rods 12 in order to disclose the construction more clearly.

Mounted upon the top surface of the cross member means 42 are bifurcated brackets 51, supporting axles 52 carrying rollers 53. The assembly of the cross member means 42, the bifurcated brackets 51 and the rollers 53 form the workpiece support assembly, generally designated 54. The upper ends of the threaded rods 39 in Figures 3 to 8 are shown to be provided with enlarged heads 55, immediately above the holes 56 in the main platen 18 through which the rods 10 39 pass.

The press may be provided with any suitable control device, and it forms no part of the present invention. As shown in Figures 1 and 2, however, a typical control arrangement consists of a servomotor 60 and a servomotor control valve 61, associated with the pump 15 and operated by the valve rod 62 connected through the links and levers 63 to 72, inclusive, to the top 73 of the vertical control rod 74. The latter is mounted, as at 75, 76 and 77, for vertical reciprocation, and carries the spaced collars 78 engaged by the bifurcated end 79 of the hand lever 80. The latter is of bellcrank form and is pivotally mounted, as at 81, upon the lower press member 11.

By moving the hand lever 80 to and fro the servomotor valve rod 62 may be caused to move to the right or left, and thereby caused to operate the servomotor 60 to shift the flow control of the pump into varying positions of forward or reverse 30 delivery of the pump 15. The pressure fluid will therefore flow through the pipe 82 for motion of the main plunger 17 in one direction, and through the pipe 83 for motion thereof in the opposite direction. The pipe 84 proceeds downwardly to 35 hydraulic devices, mounted in the bottom member 11 of the press, which likewise has the tonnage control device 85 mounted thereon and controlled by turning the hand wheel 86 (Figure 2). The tonnage control device 85 has been omitted from Figure 1 in order to avoid concealing the parts located behind it. The pump control may likewise be operated electrically through the link 87 interconnecting the lever 72 with the armature 88 of the solenoid 89. These details of the control system form no part of the present invention and hence are omitted in Figures 3 to 8, inclusive.

In the operation of the horn press of this invention, the control of the pump 15 is shifted to cause the main plunger 17 to rise and lift with it the upper die 20, the horn assembly 25 and the work-support assembly 54. If a workpiece 35 is already in the press, it is raised into the position shown in Figures 3 and 4. The lower portion 26 of the horn assembly 25 is now separated vertically from the arms 31 and 32 of the horn support 33, and the upper die 20 is likewise separated from the lower die 27. Under these circumstances, the finished workpiece 35 may be withdrawn by raising it to the dotted line position shown in Figures 3 and 4, and a new workpiece placed in the position shown by the solid lines in Figures 3 and 4 merely by reversing the procedure.

The main platen 17 is then caused to move downwardly so as to lower the horn assembly 25 into position with the horizontal portion 26 thereof resting upon the front and rear arms 31 and 32 of the horn support 33. To press the 70 workpiece the main plunger 17 is now caused to continue to move downwardly, thereby bringing the upper die 20 into engagement with the workpiece 35 resting upon the lower die 27. The workpiece may then be pressed from the rough con- 75

dition of Figure 11, through the semi-finished condition of Figure 12, into the finished and welded condition of Figure 13 by providing suitable welding apparatus (not shown), forming no part of the present invention. As the horn assembly 25 moves downwardly the work-support assembly 54 likewise moves downwardly and comes to rest upon the lugs or stops 90. As the platen 18 and main plunger 17 continue to carry the upper die 20 downwardly, however, the work-support assembly 54 remains motionless so that only the upper die 20 continues to move in the last stages of operation.

In order to accommodate varying sizes of workpieces, such as different sizes of automobile rims, the hand wheel 50 may be rotated to raise or lower the positions of the rollers 53 relatively to the lower die 27 upon which the upper part of the workpiece 35 rests. When the pressure of the upper die 20 is brought to bear upon the workpiece 35 and transmitted therethrough to the horizontal portion 26, the latter is completely supported at both of its ends by the horn support arms 31 and 32. Since the horn is not left unsupported at one end, as in prior art horn presses but is completely supported at both ends during the pressing operation, the breakage of the horizontal horn portion 26 is completely prevented. At the same time the raising of the platen 18 and the consequent raising of the horn assembly 25 immediately separate the horizontal horn portion 26 from the horn supports 31 and 32 to enable the insertion or removal of workpieces.

The automobile rims shown as the workpieces 35 are merely for the purpose of illustration and may consist of any type of workpiece of the class ordinarily processed in a horn press. The purpose of the horn press is to provide a free space for portions of the workpiece which project or extend in a direction making them incapable of being accommodated in ordinary presses.

It will be understood that I desire to comprehend within this invention such modifications as come within the scope of the claims and the invention.

Having thus fully described my invention, what I claim as new and desire to secure by Letters Patent, is:

- 50 1. In a press, a platen, a horn support, a horn connected to said platen and movable therewith out of engagement with said horn support for the insertion and removal of workpieces, a workpiece support arranged to support a portion of the workpiece when in position upon said horn, and means for connecting said workpiece support to said platen for motion thereof relatively to said horn support whereby to move the workpiece away from said horn support.
- 60 2. In a press, a platen, a horn support, a horn connected to said platen and movable therewith out of engagement with said horn support for the insertion and removal of workpieces, a workpiece support arranged to support a portion of the workpiece when in position upon said horn, means for connecting said workpiece support to said platen for motion thereof relatively to said horn support whereby to move the workpiece away from said horn support, and adjustment means for varying the distance between said work-support

and said horn for the adaptation thereof to varying sizes and shapes of workpieces.

3. In a press, a platen, a horn, a horn support having a plurality of supporting positions adapted to support said horn in the vicinity of its opposite ends, means for moving said horn into and out of engagement with said horn support, and an auxiliary workpiece support movable with said horn support for moving the workpiece in at least one direction.

4. In a press, a platen movable along an axis, a first die mounted on said platen, a horn comprising two spaced horizontal arms and a connecting vertical arm, means loosely connecting said upper horizontal arm and said platen permitting relative vertical movement between said parts, said horn movable with said platen for a portion of the stroke thereof, a second die on the lower horizontal arm of said horn, said dies being engageable at a given time with a part only 20 of the total portion of the workpiece worked upon by said dies, a horn support comprising a pair of spaced arms for supportingly engaging the opposite ends of the lower arm of said horn at the end of the motion of said horn towards said horn 25 support, said horn support arms having a cavity therebetween extending in a direction along the axis of movement of said platen away from said die a greater distance than the workpiece extends into said cavity when resting against said sec- 30 ond die.

5. In a press, a platen movable along an axis, a first die mounted on said platen, a horn comprising two spaced horizontal arms and a connecting vertical arm, means loosely connecting 35 the upper horizontal arm and said platen permitting relative vertical movement between said parts, said horn movable with said platen for a portion of the stroke thereof, a second die on the lower horizontal arm of said horn, and a 40 horn support comprising a plurality of supporting arms having a cavity therebetween extending in a direction along the axis of movement of said platen away from said die a greater distance than the workpiece extends into said cavity when resting against said second die.

6. In a press, a platen movable along an axis, a first die mounted on said platen, a horn comprising two spaced horizontal arms and a connecting vertical arm, means loosely connecting 50 said upper horizontal arm and said platen permitting relative vertical movement between said parts for automatically moving said horn into and out of engagement with said horn support in response to the working and retraction strokes 55 respectively of said platen; said horn movable with said platen for a portion of the stroke thereof, a second die on the lower horizontal arm of said horn, said dies being engageable at a given time with a part only of the total portion of the work- 60 piece worked upon by said dies, a horn support having a plurality of supporting arms adapted to support said horn in the vicinity of the opposite ends of its lower horizontal arm, said horn support arms having a cavity therebetween extending 65 in a direction along the axis of movement of said platen away from said die a greater distance than the workpiece extends into said cavity when resting against said second die.

DON L. CLEVELAND. 70
